DESIGN FOR A HANDLE FOR COOKING UTENSILS

Robert B. Wemyss, Louisville, Ky.

Application February 5, 1945, Serial No. 117,755

Term of patent 7 years

(CL D44—29)

To all whom it may concern:

Be it known that Robert B. Wemyss, a citizen of the United States, residing in Louisville, county of Jefferson, State of Kentucky, has invented a new, original, and ornamental Design for Handle for Cooking Utensils, of which the following is a specification, reference being had to the accompanying drawing forming part thereof, wherein—

Fig. 1 is a side view of a handle for cooking utensils showing my new design;

Fig. 2 is a top view;
Fig. 3 is an end view; and
Fig. 4 is a sectional view taken on line 4—4 of Fig. 2.

I claim:

The ornamental design for a handle for cooking utensils, substantially as shown.

ROBERT B. WEMYSS.
